UNITED STATES PATENT OFFICE

92,271

DESIGN FOR A CASING FOR A BOILER

Burton E. Shaw, Southwick, and Eugene V. La-
vallee, Willimansett, Mass., assignors to Gilbert
& Barker Manufacturing Company, West
Springfield, Mass., a corporation of Massachu-
setts

Application March 21, 1934, Serial No. 51,133

Term of patent 14 years

To all whom it may concern:

Be it known that we, BURTON E. SHAW and EUGENE V. LAVALLEE, both citizens of the United States, residing at Southwick and Willimansett, respectively, in the county of Hampden and State of Massachusetts, have invented a new, original, and ornamental Design for a Casing for a Boiler, of which the following is a specification, reference being had to the accompanying drawing, forming part thereof.

Fig. 1 is a perspective view of the casing of a boiler, showing our new design;

Fig. 2 is a fragmentary horizontal section through the front wall of the casing, such section

being taken about mid-way between the top and bottom of the casing, and showing the contour of the corners and the front wall and the central panel on the front wall;

Fig. 3 is a similar view taken through the upper and wider portion of the central panel on the front wall; and

Fig. 4 is a central vertical section taken through the said central panel.

We claim:

The ornamental design for a casing for a boiler as shown and described.

BURTON E. SHAW.
EUGENE V. LAVALLEE.
